Atty.

UNITED STATES PATENT OFFICE

WALTER W. ROBINSON, OF BELOIT, WISCONSIN, ASSIGNOR OF ONE-HALF TO BENJAMIN F. LYONS, OF CHICAGO, ILLINOIS

CONTAINER CONSTRUCTION

Application filed October 8, 1928. Serial No. 311,236.

These improvements relate to containers. The chief object is to provide a construction whereby strong, durable and otherwise advantageous containers, in a given size, shape 5 or form and in a large variety of sizes, shapes and forms may be made in a simple, cheap and expeditious way. Other objects and advantages will appear hereinafter.

Figure 1 of the drawings is a vertical section through a container made according to these improvements; Fig. 2 is a horizontal top view of the same with the top plate or cover removed; and Fig. 3 is an "exploded" view in perspective of the various parts, members 15 or pieces shown in other figures.

The rectangular container structure illustrated comprises a pair of oppositely disposed rectangular plate-like side members 10 and another pair of oppositely disposed rectangular plate-like side members 11. These four pieces may be considered as being cut from flat sheet metal such as aluminum, brass, iron, etc. There is also an upper plate 12 and a lower plate 13, substantially rectangular in shape, and cut from similar flat sheet stock, the corners preferably being rounded.

There are four posts of a common construction, each marked 14, and these posts extend 30 between the top and bottom plates.

Each post 14 is formed in my practice of sheet metal of the same kind of stock used for the plates. Each comprises a substantially cylindrical longitudinally extending part 15 and a pair of flanges each of which is marked 16. These flanges 16 define, with the body 15, in cross view, a substantially U-shaped recess or way 17.

In forming a rectangular container the 40 recesses or ways 17 of a given post are directed, in cross view, substantially at right angles to each other, and the space in these ways respectively, between a flange 16 and the body 15, is such as to receive and accommodate snugly the edge portion of one of the side members. In making a container of some other shape the ways or recesses 17 would be otherwise appropriately disposed angularly with respect to each other.

50 Being formed of sheet metal, the substan-

tially cylindrical body 15 is hollow interiorly. Its ends may therefore be interiorly screw-threaded to accommodate screws 18 passing through holes as 19, Fig. 3, in the top and bottom plates, and thus these top and bottom members are secured rigidly to the posts.

Preferably the top and bottom plates extend slightly beyond the side plates respectively, and the side plates are of equal height 60 with the posts. When the respective side plates have their opposite edge portions inserted in the recesses 17 of the post members which are directed toward each other, and the top and bottom members are secured to 65 the posts the side members are strongly held between the top and bottom members, and the structure as a whole becomes very strong and rigid.

One of the end members, as the lower plate 70 13, may be considered a base, and which may have any approved shape or form. From the base, as 13, there extend a plurality of posts, as many as necessary to form a given shape of container, at right angles to the base 75 and parallel to each other. The posts may be held upon the base in any approved way. Being held as described the posts present longitudinally-extending ways as 17 directed toward corresponding ways on the adjacent 80 posts respectively. The side plates, being severally cut to appropriate length and height, can be inserted, telescopically, into the proper ways, and then the lid or cover may be applied.

85 The side members in this construction are arranged in an endless series with edge portions of adjacent plates close to each other, and, omitting the top and bottom plates, they form a ring-like open-ended structure. The 90 plates which I have called the top and bottom plates 12 and 13 close the open ends of this structure. Such a ring-like structure may first be formed, in the assembly, and then the top and bottom plates may be applied; and in applying the top and bottom plates, since the substantially cylindrical part 15 is hollow, it is obvious that other forms of holding means than the screws shown may be used.

The structure is peculiarly advantageous in view of the cheapness and simplicity with which a peculiarly strong container of this character may be formed. The post material as 15 may be rolled or otherwise formed in substantially long strips and cut to length as desired. Likewise the plates are cut from stock material. According to the construction illustrated, therefore, containers of a 10 large variety of sizes, and proportions may be made, in the rapid, simple and cheap method described. Other forms or shapes may also be provided for. One notable advantage is that special dies for each size of 15 container are not required.

While the present improvements have many important uses, they have been designed chiefly as a shield against inductance or other disturbances in connection with electrical devices, particularly such as are found in radio work. In Fig. 1 I have shown the container as being mounted on a baseboard 20 by screws 21, while within the container or shield is a thermionic tube 22 operatively held upon a tube holder 23 supported by a pair of posts 24 upon the base or lower plate 13. Holes 25, Fig. 3, in plate 13 permit conductors as 26, Fig. 1, to enter the hollow interior of the container for attachment to the 30 terminals of the tube holder.

Among the many manufacturers of radio equipment there are many different requirements as to size, shape and proportions of box-like shields for the various instruments 35 and groups of them. All such requirements may be met with the one construction shown, effecting various economies.

Another advantage of the construction is that the various parts may be shipped to the 40 manufacturer in disassembled or knock-down condition, which effects a saving and greatly facilitates mounting the electrical instruments within the device, as on the base or bottom plate 13. Whether a single instrument or several of them be mounted in a single container, the manufacturer of the set can do this most readily by mounting them upon the base 13 free and independent of all other container parts. The corner posts may then 45 be applied, and then the top plate.

The user of the device can always gain ready access to the hollow interior by simply removing the top plate. With that plate removed the structure is still firmly coordinated, since the posts are firmly secured to the base and the corner pieces or posts are strongly interlocked with the side plates.

The invention is not limited to size nor to an all-metal construction. The utility of 60 good appearance is also present.

I contemplate as being included in these improvements all such changes, variations and departures from what is thus specifically illustrated and described as fall within the 65 scope of the appended claims.

I claim:

1. Container construction comprising a pair of end plates, corner posts extending between said plates, each of said posts comprising a substantially cylindrical body and a 70 pair of longitudinally extending flanges forming with the cylindrical body a pair of substantially U-shaped ways, the ways being directed angularly with respect to each other and the body being within the angle defined by the ways, side plates respectively extending into ways of adjacent posts and positioned between the end plates, and means holding the end plates upon said posts.

2. A post for container construction of the 80 character described comprising a relatively long substantially cylindrical body having a pair of flanges forming with the body a pair of ways directed substantially at right angles with respect to each other in cross view and with the body within the angle defined by the ways, each way being adapted to receive the edge portion of a plate-like side member.

3. A post for container construction of the 90 character described comprising a relatively long substantially cylindrical body having a pair of flanges forming with the body a pair of ways directed angularly with respect to each other in cross view, each way being adapted to receive the edge portion of a plate-like side member, said body being hollow and its end portions being interiorly screw-threaded.
